UNITED STATES PATENT OFFICE.

HENRY TESSEYMAN, OF DAYTON, OHIO, ASSIGNOR TO THE BARNEY & SMITH CAR COMPANY, OF SAME PLACE.

TRUCK AND BODY BOLSTER FOR CARS.

SPECIFICATION forming part of Letters Patent No. 592,028, dated October 19, 1897.

Application filed August 24, 1897. Serial No. 649,318. (No model.)

To all whom it may concern:

Be it known that I, HENRY TESSEYMAN, a citizen of the United States, residing at Dayton, in the county of Montgomery and State of Ohio, have invented certain new and useful Improvements in Truck and Body Bolsters for Freight and Passenger Cars; and I do hereby declare that the following is a full, clear, and exact description of the invention.

My invention relates to improvements in truck and body bolsters for freight and passenger cars, its object being to so construct such bolsters as to reduce the cost thereof and increase their durability, and with such ends in view the invention consists in certain novel details of construction, which will be herein-after fully described, pointed out in the claims, and shown in the accompanying drawings, forming part of this specification, and in which—

Figure 1 is a broken perspective view of the invention, showing the relative positions of the two bolsters and the floor-sills of a car mounted on the body-bolster, one half being shown in full and the other half in section through the longitudinal center of the bolsters; and Fig. 2, a broken perspective view of the end casting or filling-block by which the separate sections of the transom-bolsters are united.

Similar letters and figures indicate corresponding parts in the drawings.

Each bolster is composed principally of two iron or steel channel-bars A and B, the top bar A of the upper or body bolster being straight and the lower bar B being so formed that for a short distance from its ends and center it is parallel with the top bar, and then angles upwardly from the center to the end parallel portions, while both sections of the lower or truck bolster are formed like the lower section of the body-bolster. The edges of the side flanges 1 of the channel-bars are brought together, or nearly so, at their ends, where the two sections are firmly bound together by filling-blocks C, preferably cast and cored out on the inside to reduce their weight, in the manner hereinafter explained. On the top and bottom of these blocks are formed annular collars or bosses 2, and on two opposite

sides lugs or bosses 3 are formed on the outsides, while the insides are provided with vertical ribs 4, extending from top to bottom, and in the filling-blocks used for uniting the truck-transom there are horizontal ribs 5 extending from one side to the other, the function of the ribs being to contribute strength to the hollow structure, through which holes 6, 7, and 8 are cored or bored, as more clearly shown in Fig. 2. One of the filling-blocks is placed between the sections at each end of the bolster, the sides 1 of the channel-bar sections overlapping two sides of each block. Holes 9 are pierced through the flat surface 10 of each of the channel-bar sections to engage the annular collars 2 of the filling-blocks, and the side flanges 1 are cut away to engage and to coact with the lugs 3 in resisting the end strain on the said side flanges.

The side sills of the car-body are represented by the letter D and the intermediate sills by the letter E, and they rest on the body-bolster as shown.

Bolts 11 extend from the under side of the body-bolster through the holes 6 and through the side sills, the sections of the bolster being otherwise secured together by rivets or bolts 12, which pass through the same and through the holes 7 of the filling-blocks, while those of the truck-bolster are secured entirely by rivets or bolts 12, which pass through the holes 6 and 7 of the filling-blocks.

Distance-posts F interpose the two sections of each bolster between the ends thereof and which are bound firmly together by bolts 13, 14, and 15, the bolts 13 passing up through the sections, the distance-posts, and the outside intermediate sills, while the bolts 14 perform the same function in connection with the two center sills and the further function of securing a center-bearing plate G to the under side of the body-bolster, and the bolts 15 extend through the two sections of the truck-bolster, the intermediate posts F thereof, and through a center-bearing plate H, mounted on the upper side of the bolster, and bind the said parts firmly together. The center bearing is composed of two parts I J, which are of usual construction. An ordinary king-bolt K passes through both bolsters and

through the center bearing in the customary manner.

Side bearings L M are secured to the bolsters, as shown in Fig. 1, although they may 5 be otherwise constructed and arranged, as may also the center bearings, on which the body-bolster rotates. The usual form of chafe-plates are bolted to the sides of the truck-bolster, at the ends thereof, by bolts 10 which extend through the holes 8 in the filling-blocks.

It will be observed from the foregoing description of my improved bolsters that they are of simple construction and of light weight 15 in proportion to their required strength.

Having thus fully described the invention, I claim—

1. A bolster for railway-cars consisting of two channeled sections bent to desired shape, 20 filling-blocks located within said sections, at the ends thereof, bosses formed on the top and bottom of said filling-blocks to engage corresponding holes in the flat surfaces of said sections, and means for rigidly securing 25 said sections to said filling-blocks, substantially as set forth.

2. A bolster for railway-cars consisting of two channeled sections bent to desired shape, filling-blocks located within said sections, at 30 the ends thereof, bosses formed on the top and bottom of said filling-blocks to engage corresponding holes in the flat surfaces of said sections, means for rigidly securing the flat surfaces of said sections to said filling- 35 blocks, and lugs or bosses formed on opposite sides of the latter to engage cut-outs in the

side flanges of said channeled sections, substantially as set forth.

3. In truck and body bolsters for railway-cars, the combination of a truck-bolster and 40 a body-bolster, each composed of two channeled sections bent to desired shape, filling-blocks located within said sections at the ends thereof, bosses formed on the top and bottom of said filling-blocks to engage corresponding 45 holes in the flat surfaces of said sections, means for rigidly securing said sections to said filling-blocks, and side and center bearings located between said bolsters, substantially as set forth.

4. In truck and body bolsters for railway-cars, the combination of a truck-bolster and a body-bolster, each composed of two channeled sections bent to desired shape, filling-blocks located within said sections at the ends 55 thereof, bosses formed on the top and bottom of said filling-blocks to engage corresponding holes in the flat surfaces of said sections, means for securing the flat surfaces of said sections to said filling-blocks, lugs or bosses 60 formed on opposite sides of the latter to engage cut-outs in the side flanges of said channeled sections, and side and center bearings located between said bolsters, substantially as set forth.

Witness my hand to the foregoing specification on this 21st day of August, 1897.

HENRY TESSEYMAN.
